Des. 183,438
Patented Aug. 26, 1958

183,438

COMBINATION CHAIR-DESK

Herbert E. Williams, Temple, Tex.

Application May 14, 1957, Serial No. 46,170

Term of patent 14 years

(Cl. D15—8)

Figure 1 is a perspective view of a combination chair-desk embodying my new design;

Figure 2 is a top plan view thereof;

Figure 3 is a rear elevational view thereof;

Figure 4 is a side elevational view thereof; and

Figure 5 is a bottom plan view thereof.

The dominant features of the design are shown in full lines.

I claim:

The ornamental design for a combination chair-desk, substantially as shown and described.
